United States Patent Office

Des. 208,905
Patented Oct. 17, 1967

208,905

BUILDING

Resta S. Gregoire, Rte. 3, Newport, Pa. 17074

Filed Nov. 9, 1966, Ser. No. 4,594

Term of patent 14 years

(Cl. D13—1)

FIG. 1.

FIG. 4.

FIG. 2.

FIG. 3.

FIGURE 1 is a plan view of a building of the present design, the dotted lines being disclosed for illustrative purposes only,

FIGURE 2 is a corner elevational view thereof,

FIGURE 3 is a side elevational view thereof, and

FIGURE 4 is a similar corner elevational view of a modification of the same design having a steeper pyramidal form and a lower base line for the lower inverted pyramidal portion of the building.

I claim:

The ornamental design for a building, as shown and described.
